INSULATING REFRACTORY WALL

George P. Reintjes, Kansas City, Mo.

Application December 28, 1936, Serial No. 117,779

7 Claims. (Cl. 72—101)

This invention relates to insulating walls for furnaces whereby walls may be constructed in integral panels comprising unit sheets or plates carrying light-weight insulating firebrick on their inner sides, the object of the invention being to provide a construction of this general character in which the panel is provided with brick engaging members supporting the brick columns against downward and inward movement.

10 A further object of the invention is to provide a unit panel construction of the general character outlined, in which the vertical load may be transmitted by tile engaging castings carried by the panels on suitable horizontal members carried by the buckstays or uprights.

A still further object of the invention is to produce a construction of the general nature outlined which may be constructed almost entirely of common brick shapes, it being necessary only 20 to present two corners of the highly friable insulating brick to a grinding wheel of any kind to form dovetail portions at the corners, or, of course, the brick may be preformed of such shape.

With the general objects named in view and others as will hereinafter appear, the invention 25 consists in certain novel and useful features of construction and organization of parts as hereinafter described and claimed; and in order that it may be fully understood, reference is to be had 30 to the accompanying drawing, in which:

Figure 1 is a fragmental perspective view of the wall of a furnace as it will appear with one form of the unit panel construction of the invention.

Figure 2 is a horizontal section taken through 35 a fragment of the wall as it appears in Figure 1.

Figure 3 is a horizontal section taken through a panel construction accommodating the length of one brick.

Figure 4 is a cross section through a hanger 40 forming a part of the invention.

Figure 5 is a perspective view of a common insulating fire brick as it will appear with two of its corners ground off to make a dovetail interlock so that it may be threaded into position as 45 shown in Figures 1, 2 and 3.

Figures 6 and 7 are respectively perspective views of modified forms of brick, one directly underlying a brick column and the other directly overlying a brick column.

50 In the said drawing, where like reference characters identify corresponding parts in all of the figures, 1 is an upright or buckstay, which, as common in furnace constructions, are spaced any desired distance apart, and secured to the inner face of said uprights may be a series of verti-

cally spaced horizontally extending supports 2, shown in the present case as of T form. The stem of the T's is secured by right angle clips 3 fastened to the buckstays 1 in any suitable way. With such a construction, it will be evident that 5 the furnace skeleton will be divided into horizontal belts by the supports 2.

The wall proper, or the panel members, to fill in between the horizontals, comprises a plate member 4 having a pair of its side edges formed with inturned flanges 5 in the construction as shown, said flanges being on the vertical edges of the plate when positioned in a wall. The flanges are not coextensive with the vertical length of the plate, but are set back from the 10 ends of said plate to leave straight or flat extensions 6 which are bolted or otherwise secured as by clamp bars 7 and eccentrics 8, illustrated in Figure 1, to the horizontal supports. Bolted or otherwise secured to the flanges are reinforce 15 castings 9, which are integrally formed with brick-engaging extension or lips 10, said castings being secured in such positions that the lips are inclined toward each other, so that they form dovetail portions (see Figure 3), engaging notches 20 11 cut out in the opposite corners of a brick 12 and thus prevent horizontal displacement of the brick.

The lower ends of the casting are provided with flanges 13 which underlie the lowermost 30 brick and constitute a shelf or support for the overlying column threaded down between the lips 10. Of course, the sheets can be made of any desired width, and are not limited to one brick length as shown in Figure 3. In Figure 1, for 35 example, the panel or sheet is of sufficient width to accommodate the length of two endwise abutting brick the abutting or adjacent brick ends, having their dovetail corners interlocked with the opposite flange 14 of a relatively U-shaped 40 hanger 15 secured by bolts or otherwise, in the central vertical axis of the sheet, and having supporting flanges 15a at its lower end, as clearly apparent in the drawing. The bottoms of the casting may be so designed that the vertical load 45 may be transferred directly to the horizontal supports by the castings, to relieve the panel of as much load as possible, although, of course, a heavier panel could be used making such load transfer unnecessary or undesirable.

The space between superimposed panels bridging the vertical height of the horizontals may be provided with any suitable firebrick protection. In the construction here illustrated, the two topmost brick are respectively a brick 16 and a 50 55

brick 17, to produce the stepped expansion joint 18. Resting on top of the brick 17 is a brick 19, which is not interlocked as here shown against inward horizontal movement. Resting on top of the brick 19 is one of the stepped brick 17 which also is not locked against inward movement. A second stepped expansion joint is now provided by threading one of the brick 16 on the castings of the superposed plate for cooperation with the brick 17.

With a construction of the type shown, it will be evident that the brick may be placed in threaded position, if desired, even before the panel is elevated. The panel is placed in position 15 from outside the combustion chamber, preferably by bringing the lower ends of the castings into rocking engagement with the horizontal support, the projecting flanges 6 of the plates resting against the outer face of the T-head of such 20 supports. The panel may now be rocked to throw its upper flange portion into contact with the outer side of the immediately overlying horizontal. The panel may now be secured in position by the means above described, or by bolts, 25 or otherwise, as found most convenient or desirable.

If the panel is of the double width as shown in Figure 1, the space between the oppositely extending flanges or lips of the center casting, is 30 preferably packed with insulating material 19a before the brick are placed in position on the panel. Suitable insulating lining 20 may also be placed between the flanges and between the plates and the outer sides of the brick, if desired.

35 The vertical edges of adjacent panels are spaced apart any desired distance depending on the exact proportions of the dovetail parts, and then the space or vertical extending pocket thus formed between panels, may be packed with any 40 suitable insulating material 21. The gap is finally closed from outside the furnace wall by batten strips 22, secured by self-threading bolts or the like, tapped into the edges of the panels as illustrated.

45 It will be apparent from the above description that any damaged panel may be quickly and easily removed as a unit from any part of a furnace wall for repair of firebrick. Or, if desired, any entirely new panel may be swung into 50 the gap opened by the removal of a panel, without any material difficulty or complicated maneuvering with a resultant loss of time or expense.

From the above description it will be apparent 55 that I have produced a construction embodying all of the features of advantage set forth as desirable; and while I have described and illustrated the preferred embodiments, it is to be understood that I reserve the right to make all 60 changes within the spirit of the invention and without the ambit of the prior art.

I claim:

1. An insulating wall for furnaces comprising a metal panel member having a pair of its opposite side edges provided with firebrick engaging means extending from bottom to top of the panel and inclined toward each other for interlocking and engagement with the opposite ends of a brick, 65

and means adjacent one edge of the panel constituting a support for such column of brick.

2. An insulating wall for furnaces comprising vertical uprights, vertically spaced horizontally extending members carried by the uprights, a rectangular metal plate having brick engaging portions along two of its opposite vertical edges, the other two side edges of the plate projecting beyond the ends of the tile engaging portions of the first two side edges and being secured to a pair of said horizontal members.

3. An insulating wall for furnaces comprising uprights, vertically spaced horizontally extending supports carried by the uprights, a metal panel member spanning the space between adjacent horizontal supports, and brick engaging members carried along opposite vertical edges of said panel and formed at their lower ends with flanges adapted to support the weight of vertical brick columns, the upper edge of said panel having frictional sliding engagement with the upper horizontal support.

4. An insulating wall for furnaces comprising uprights, vertically spaced horizontally extending supports carried by the uprights, a metal panel member spanning the space between adjacent uprights, brick engaging members extending vertically along opposite edges of the panel and inclined inwardly toward each other, said engaging members having brick supporting flanges at their lower ends, and a column of brick resting on the flanges and held against movement away from the panel by interlocking engagement with the vertically extending brick engaging members.

5. An insulating wall for furnaces comprising uprights, vertically spaced horizontally extending supports carried by the uprights, a metal panel member spanning the space between adjacent uprights, brick engaging flanges extending vertically along opposite edges of the panel and inclined inwardly toward each other and having supporting flanges at their lower ends, and a column of firebrick having notched outer corners interlocked with the vertical flanges, the undermost brick resting on the supporting flanges.

6. An insulated refractory wall, comprising an upright sheet metal panel, brick engaging members extending vertically along opposite edges of the panel and inclined inwardly toward each other, a brick supporting shelf adjacent the lower edge of the panel, and a brick column carried by said shelf, each brick of the column being interlocked with the brick engaging members against lateral movement away from the panel.

7. An insulated refractory wall comprising in combination with a horizontal support, of a panel member having its lower edge overlapping the outer face of the support, a plurality of vertical rows of brackets projecting inwardly from the face of the panel member beyond the inner face of and having their lower ends resting on the support, a brick shelf adjacent the lower ends of the brackets, and a column of brick carried by the shelves and interlocked against lateral movement with said brackets.

GEORGE P. REINTJES.
